UNITED STATES PATENT OFFICE

LEWIS A. JARVIS, OF GRAND RAPIDS, MICHIGAN, ASSIGNOR TO W. B. JARVIS COMPANY, OF GRAND RAPIDS, MICHIGAN

CAP FOR RADIATOR NECKS AND THE LIKE

Application filed March 14, 1932. Serial No. 598,747.

The main objects of this invention are:

First, to provide an improved cap for radiators, gasoline tanks and the like which may be quickly opened and closed and when closed 5 provides an effective seal.

Second, to provide a cap or closure of this type which may be readily applied to standard types of motor vehicles.

Third, to provide a cap or closure of this 10 type in which the parts are so assembled that they are not likely to fall or drop into the radiator or tank on which the cap is used.

Objects relating to details and economies 15 of my invention will appear from the description to follow. The invention is defined and pointed out in the claims.

A structure which is a preferred embodiment of my invention is illustrated in the accompanying drawings, in which:

20 Fig. 1 is a vertical section of a radiator cap embodying the features of my invention, taken on line 1—1 of Fig. 2, the cover being closed.

Fig. 2 is a perspective view, showing the 25 cover in its open position.

Fig. 3 is a detail section of the cover.

Fig. 4 is a perspective view of the hinge member.

Fig. 5 is a perspective view of the gasket 30 backing disk.

Fig. 6 is a perspective view of the gasket.

Fig. 7 is a perspective view of the screw and gasket support assembly, and

Fig. 8 is a fragmentary detail section of 35 the body member, showing the set screw for securing the body member to the neck of a container such as a radiator.

In the accompanying drawings, 1 represents a radiator neck of the externally 40 threaded type, but it is desired to point out that my improvements are readily adapted for radiators or the necks of tanks of the bayonet type. I have not, however, shown such an adaptation as joints of that type are 45 well known in the art.

The end 2 of the neck 1 constitutes a seat for the gasket 3 which is supported by the downwardly facing shoulder 4 of the closure body member 5. A set screw 6 is provided 50 for locking the body member upon the

threaded neck, the body member being preferably permanently attached to the neck. The same would be true if a bayonet type of joint were provided between the body member and the neck.

55

The body member is provided with an upwardly facing convexly curved annular gasket seat 8, the gasket 9 being supported for coaction with this gasket seat between the resilient closure disk 11 and the stepped support 10.

60

The gasket itself is preferably of a yielding resilient material although it is yielding- 65 ly supported by the resilient closure and an effective seal is provided when it is made of quite hard material such, for example, as fiber.

The support 10 is secured to the cover 12 by means of the screw 13, the head 14 of which is disposed within the support 10. A 70 retaining disk 15 is secured to the support preferably by the rivet 16, this disk having a central tool opening 17 of such diameter as to prevent the screw passing therethrough, so that the screw is rotatably secured or 75 swiveled to the support.

The cover 12 is provided with an annular stud 18 into which the reduced portion or smaller portion of the support is engaged, this support being stepped or shouldered to 80 project into the stud and to support the disk which is arranged on the end of the stud and has a central opening registering with the stud. The support also has a shoulder which properly centers the gasket. This assembly 85 also secures the cover to the annular hinge member 20, the opening of which receives the stud, the hinge member having a pintle 21 engaging the vertically elongated pivot hole 22 in the pintle ear 23 of the body member. 90 This arrangement permits a limited vertical movement of the cover when it is closed.

The cover is locked in its closed position and clamped upon the gasket 9 by means of the cammed keeper lugs 24 projecting from 95 the body member to coact with the slots 25 in the latching lugs 26 on the depending rim or skirt 27 of the cover.

The cover is also provided with internal 100 spaced stops 28 which limit the rotative move-

ment of the cover relative to the body member. The cover is quickly released or locked by a rotative movement thereof, and at the same time provides an effective joint or seal.

- 5 The parts are so assembled that there are no small parts to drop into the radiator or tank should they become loosened or detached. The screw, being swivelly attached to the support, is not easily lost and cannot easily 10 drop into the tank, the openings of which are ordinarily of a diameter exceeding the support. The parts are so related that a single screw is all that is required.

I have illustrated and described my improvements in an embodiment which I have found very practical. I have not attempted to illustrate or describe certain embodiments or adaptations contemplated as it is believed that this disclosure will enable those skilled 20 in the art to embody or adapt my improvements as may be desired.

Having thus described my invention, what I claim as new and desire to secure by Letters Patent, is:

- 25 1. The combination with a body member having an upwardly facing annular gasket seat, of an annular hinge member pivoted to said body for limited vertical movement when the cover is closed, a cover having an annular 30 stud disposed in said hinge member and rotatable therein, a resilient closure disk disposed on the end of the stud and having central openings registering with the opening in the stud, a gasket having a central opening 35 therein larger than said closure disk disposed on the underside thereof, a support member having a central part disposed through said opening in said closure disk and engaged within said stud, said support being shouldered to engage said closure disk and said gasket, and coacting 40 latch lugs and keepers on said cover and body member adapted to be engaged and disengaged by a rotative movement of the cover relative to said body member.

- 45 2. The combination with a body member having an upwardly facing annular gasket seat, of an annular hinge member pivoted to said body, a cover having an annular stud disposed in said hinge member and rotatable therein, a resilient closure disk disposed on the end of the stud and having central openings registering with the opening in the stud 50 a gasket having a central opening therein larger than said closure disk disposed on the underside thereof, a support member having a central part disposed through said opening in said closure disk and engaged within said stud, said support being shouldered to engage

said closure disk and said gasket, a screw threaded into said cover and having a head disposed within said support member, and a retaining disk secured to said support member and having a tool opening of a less diameter than the head of the screw whereby the screw is rotatably retained within the support.

3. The combination with a body member having an upwardly facing annular gasket seat, of an annular hinge member pivoted to said body for limited vertical movement when the cover is closed, a cover having an annular stud disposed in said hinge member and rotatable therein, a resilient closure disk disposed on the end of the stud and having central openings registering with the opening in the stud, a gasket having a central opening therein larger than said closure disk disposed on the underside thereof, a support member secured to said cover and having a central part disposed through said opening in said closure disk and engaged within said stud, said support being shouldered to engage said closure disk and said gasket, and coacting 90 latch lugs and keepers on said cover and body member adapted to be engaged and disengaged by a rotative movement of the cover relative to said body member.

4. The combination with a body member having an upwardly facing annular gasket seat, of an annular hinge member pivoted to said body, a cover having an annular stud disposed in said hinge member and rotatable therein, a resilient closure disk disposed on the end of the stud and having central openings registering with the opening in the stud, a gasket having a central opening therein larger than said closure disk disposed on the underside thereof, and a support member secured to said cover and having a central part disposed through said opening in said closure disk and engaged within said stud, said support being shouldered to engage said closure disk and said gasket.

5. The combination with a body having an upwardly facing gasket seat, of a hinge member pivoted to said body, a cover having an annular stud rotatably engaging said hinge member, said cover and body member having coacting latch lugs and keepers arranged to be engaged and disengaged by a rotative movement of the cover, a resilient closure disk disposed on the end of said stud, a gasket having a central opening therein, a stepped gasket and closure disk support member disposed through said openings in said gasket and closure disk and engaged within said stud, and an attaching screw for said support member swivelly retained therein.

6. The combination with a body having an upwardly facing gasket seat, of a hinge member pivoted to said body, a cover having an annular stud rotatably engaging said hinge member, said cover and body member having

coacting latch lugs and keepers arranged to be engaged and disengaged by a rotative movement of the cover, a resilient closure disk disposed on the end of said stud, a gasket having a central opening therein, and a stepped gasket and closure disk support member disposed through said openings in said gasket and closure disk and secured within said stud.

10 In witness whereof I have hereunto set my hand.

LEWIS A. JARVIS.
